SCRAP BUNCH MACHINE

John F. Halstead, Brooklyn, N. Y., assignor to
 International Cigar Machinery Company, a
 corporation of New Jersey

Application September 25, 1934, Serial No. 745,470

46 Claims. (Cl. 131—42)

This invention relates to scrap bunch cigar machines, the machine herein described being an improvement on the machine disclosed in Patent No. 1,915,525, granted June 27, 1933, on the application of F. C. Gladeck, et al. The improved machine consists of a stationary tobacco magazine or hopper provided with intermittently oscillating agitators adapted to rake the tobacco towards the outlet of the hopper, an oscillating transfer pocket beneath the hopper outlet, an automatically operated spill catcher beneath the transfer pocket, a measuring chamber provided with an automatic gate adapted to be opened to admit tobacco discharged from the transfer pocket and the spill catcher, charge-compressing mechanism controlling the operation of the transfer pocket, a charge-cutting and transfer unit including a swinging charge-measuring pocket, and a bunch rolling mechanism.

The scrap tobacco is placed in the hopper in which it is agitated and carried from both sides thereof towards a centrally located outlet by two sets of agitators which are so actuated as to move the tobacco mass on their forward swing but to leave it practically undisturbed on their return swing. Below the outlet of the hopper is an oscillating horizontal drum-shaped structure containing a transfer pocket which is periodically closed and opened by automatically controlled coating knives. In each cycle of the machine this pocket makes one-half revolution and returns to starting position. While in the starting position, the pocket-closing knives are open so that tobacco raked by the agitators can fill the pocket. Thereupon the drum makes its forward half-turn, at the start of which the knives are closed and at the end of which they are reopened, permitting the charge to drop into a measuring chamber therebelow, the cam-operated gate of the transfer pocket. After the pocket has returned to starting position, the knives, which were closed upon movement of the pocket from the delivery position, are again opened to receive a new charge, and the gate of the measuring chamber is closed and the column of loose tobacco therein is pushed by a horizontally slideable spring-tensioned plunger into a charge-measuring pocket into which it is thereby compressed to the proper density determined by the adjustment of the plunger spring. Beneath the discharge opening of the housing in which the transfer pocket oscillates there is pivoted a curved tray linked to the operating lever of the measuring-chamber gate; this tray covering the said discharge opening while said gate is closed, thus catching any tobacco which may have been delayed in its fall through the discharge opening until the gate is closed, and discharging it into the measuring chamber when the gate is open.

To provide against scanty bunch charges, the transfer pocket, as in the machine of the patent referred to above, is designed to hold an excessive quantity of tobacco, and the compressing plunger is provided with the ratchet drive described in the patent cited above to stop the oscillation of the pocket for one cycle whenever surplus tobacco sufficient at least for a full charge has accumulated in the measuring chamber. The cross-section of the charge-measuring pocket, instead of having a height greater than its length, is made of decreased height and correspondingly increased length so that the extent of the stroke of the charge-cutting knife necessary to sever a charge is materially reduced. The charge-measuring pocket with the cut charge is then turned into vertical position so that the horizontal length of the chamber becomes the height of the bunch charge delivered to the rolling apron, the charge ejecting plunger acting on the inner end of the charge and compressing it to a substantially square section. Accordingly, the main object of the invention is the production of an improved machine having a novel combination of elements and a novel mode of operation.

In the accompanying drawings which form a part of this specification and in which like characters of reference indicate the same or like parts:

Fig. 1 is a side elevation of the improved scrap bunch machine;

Fig. 2 is an end elevation of the same, on line 2—2 of Fig. 1;

Figs. 1A and 2A are detail sections of Figs. 1 and 2, respectively, showing the drive of the hopper agitators;

Fig. 2B is a detail plan view on line 2B—2B of Fig. 1;

Fig. 3 is an enlarged side elevation of the charge receiving and transfer unit;

Fig. 4 is a sectional end elevation of the same, on line 4—4 of Fig. 3;

Fig. 5 is an enlarged end elevation of the charge cutting and delivery unit, on line 5—5 of Fig. 1;

Fig. 6 is a side elevation on line 6—6 of Fig. 5; and

Fig. 7 is a plan view on line 7—7 of Fig. 5.

In carrying the invention into effect there is provided a hopper for holding a supply of scrap tobacco, the hopper being provided with an out-

let, a transfer pocket underlying said outlet, a measuring chamber underlying the pocket and provided with a hinged gate adapted to be swung open to admit tobacco to the measuring chamber, 5 mechanism for intermittently oscillating the pocket to move it into registry with the outlet of the hopper to receive a quantity of tobacco therefrom and then carry said quantity into position above the measuring chamber for delivery thereto, 10 means independent of said mechanism for swinging open the gate while the pocket is in filling position and keeping the gate open while the pocket oscillates, knives coacting to separate the quantity of tobacco in the pocket from the mass 15 of tobacco in the hopper and then confine it in the pocket while it is being carried into position above the measuring chamber, means for closing and separating the knives, means for compressing the tobacco deposited in the chamber, and means 20 for severing a bunch charge from the compressed column of tobacco in the chamber and transferring the severed charge to bunch rolling position. In the best constructions contemplated there is also provided opposed sets of oscillatory agitators 25 in the hopper for raking the mass of tobacco from the sides of the hopper toward the outlet, and the charge-severing and transferring means includes a vertically reciprocable slide-rod, a charge-cutting knife supported from said rod, a charge-measuring pocket normally supported from said rod in a horizontal position aligned with the measuring chamber to form a continuation thereof, a device for turning the pocket into vertical position after the charge therein has been severed 30 by the knife, and mechanism for ejecting the charge from the pocket when the latter is in a vertical position.

These various means and parts may be widely varied in construction for the particular machine 40 selected to illustrate the invention is but one of many possible concrete embodiments of the same. The invention, therefore, is not to be restricted to the specific construction shown and described.

Referring to Figs. 1 and 2, side frames 15, 15' 45 support a table 16 upon which are mounted pedestals 17, 17', a support block 18, and a pedestal frame 19. The frames 15 also support the main shaft 20 of the machine which is driven in the manner shown in the above mentioned 50 patent. The shaft 20 carries cams 25, 26 and 27 which actuate cam levers fulcrumed on a shaft 29 journaled in frame 15 and a bearing 28.

The pedestals 17, 17' support the hopper 30 and carry a shaft 31 on which the oscillatory transfer pocket 63 is mounted, as will be presently 55 described. The support block 18 carries the measuring chamber 33 and the bar 34 on which the charge-compressing plunger 35 is slidably mounted as hereinafter described. On the 60 pedestal frame 19 is mounted the charge-measuring pocket 36, normally forming a continuation of the measuring chamber 33, and constituting a part of the charge-cutting and transfer unit 37. To the base 16 is attached the bunch rolling table 65 38 over which swings the bunch rolling pin 39 carried by an arm 40 fulcrumed on a shaft supported by side frames 15, 15'.

The mass of tobacco T in hopper 30 is raked 70 towards the outlet in the bottom of the hopper by pairs of agitator rods 41, 41' fixedly mounted on shafts 41 and 42 in the ends of a counter-balanced lever 43 pivoted on a bracket 44 attached to one side of the hopper 30. The bracket 44 carries a shaft 49 which is intermittently driven from a 75 shaft 21 in pedestal 17 by means of sprockets 50

and 51 and chain 52. The shaft 21 is oscillated by means of the arm 22 fixed thereon and connected by a rod 83 to a cam lever 84 having a roller 85 in engagement with the track of the face of cam 25. A pawl 23 carried by an arm 24 fixed to shaft 21 engages with a ratchet 45 attached to sprocket 50 which is loose on shaft 21. A retaining pawl 23' pivoted on pedestal 17 prevents the ratchet from turning backward on the return of the driving pawl 23. On shaft 49 is mounted a crank 46 connected by a bar 48 to shaft 42. The bar 48 is in turn connected by a link 57 to an arm 58 on shaft 41. By this linkage the ends of agitators 41 are forced to describe a path 59, Fig. 1, and the ends of agitators 41' 15 describe a path 60, the advance of the agitators along these paths causing the mass of tobacco in the hopper to be raked by the agitators from both sides of the hopper towards the centrally located outlet, while their return movement 20 causes the agitators to move more or less axially and thus not to affect the tobacco mass to any substantial degree.

To prevent jerkiness in the motion of the agitators due to the change of relative position of the 25 counterweight of balance arm 43, the sprocket 51 has attached to it a concentric ring 61 into an annular internal groove of which an open circular spring 62 is inserted, Figs. 1A and 2A. One of the inturned ends of this spring, namely the 30 trailing end with respect to the direction of rotation of the ring 61, engages a pin 68 fastened in bracket 44 so that the sprocket 51 in turning has to overcome the friction of spring 62 against ring 61, thereby providing a smooth motion of the 35 agitator linkage.

This improved motion is quite important because it assures complete filling of the transfer pocket. The old type agitator moved in one direction only and tended to lift the tobacco up 40 against the rear corner of the hopper with the result that it packed the tobacco there so hard that it would break the hinges of the cover. With the old construction the side of the hopper from which the agitators moved would be left empty 45 and therefore tend to leave the corner of the pocket adjacent that side empty with resultant lack of uniformity of the bunch charges, especially when the tobacco was low in the hopper.

The shaft 31 is journaled in the pedestals 17, 50 17' and alternately turned forward and back by means of a gear 53 thereon meshing with a reciprocating rack 54 connected by a rod 70 to a cam lever 55 carrying a roller 56 engaging in the track of face cam 25. The rack 54 is guided by 55 a flanged roller 71 turning on a stud carried by pedestal 17. Loose on shaft 31 are gear segments 72 and 73, Figs. 3 and 4, to the hubs of which are keyed the transfer pocket 63 and the arm 74 respectively. The arm 74 carries an arcuate knife 66 coacting with the arcuate knife 67 fastened to a spider 75 keyed to shaft 31 to separate the quantity of tobacco in the pocket 63 from the mass of tobacco in the hopper 30 from which the pocket is filled, and confine said quantity in the pocket, as will be presently described. The hub of pocket 63 carries radial spokes 76, and the guide ring 32 at one end of the pocket 63 is secured thereto and to the spokes 76 by screws passing through countersunk holes 70 in the ring, the guide ring 32 at the other end of the pocket 63 being secured to that end of the pocket 63. The pocket 63 is provided with removable inserts 64 which may be replaced by inserts of different thickness to adapt the ma- 5

chine to bunches of widely differing sizes, and the outer side faces of the pocket 63 are fitted with resilient pads 65 which act as buffers for the lever 74 and the spider 75 in their closed position. One arm of the spider 75 carries a horizontal shaft 77. On the inner end of the shaft 77 are keyed two epicyclic gears 78 and 79 meshing with the gear segments 72 and 73, respectively, to oscillate the pocket 63 and lever 74, as will be presently described.

While the pocket is in transit from filling to discharging position the knives 66 and 67 are normally held closed by coil springs 68, 68' anchored to posts 104 and 104' in the rings 32, the spring 68 being connected to a post 105 in arm 75, and the spring 68' being connected to a post 106 in a lug 107 of arm 74. When the pocket 63 is in filling position the lug 107 rests against a stop screw 109, Fig. 2, carried by a block 110 attached to pedestal 17, thereby holding the knife 66 open, the knife 67 having been relatively moved into open position with respect to pocket 63 by means which will now be described.

During the downstroke of the rack 54 the shaft 31 is turned in a clockwise direction, as viewed in Fig. 1, and the spider 75 moves the knife 67 inwardly over the pocket 63 while the latter is at filling position, until the spider 75 meets the buffer 65 on pocket 63, whereupon the latter is also turned in a clockwise direction and swung away from its filling position under the outlet of the hopper 30. Upon movement of the pocket 63 away from filling position the lug 107 is disengaged from the stop screw 109, permitting the spring 68' to pull the arm 74 toward the pocket 63 and move the knife 66 inwardly thereover until the arm 74 meets the buffer 65 on pocket 63 to coact with the knife 67 to sever any scraps of tobacco which may project between the knives 66 and 67 and then confine the tobacco in the pocket 63. While the spider 75 is moving toward the pocket 63 and the knife 66 is being moved inwardly thereover by the arm 74, the gear segment 73 keyed to arm 74 turns the epicyclic gear 79 with the shaft 77, thereby causing the epicyclic gear 78 to drive the gear segment 72 to turn the pocket 63 toward the spider 75 until it meets the latter. Upon engagement of spider 75 with the pocket 63, the epicyclic gears 78 and 79 remain idle on the shaft 77 until the arm 80 on the latter meets the stationary roller 81 supported by a bracket 88 attached to pedestal 17, at which time the pocket 63 is moving into discharging position. As the arm 80 is thus turned back by the roller 81 the shaft 77 is turned back with the epicyclic gears 78 and 79, whereby the gear 78 drives the gear segment 72 and moves the pocket 63 relative to the knife 67 into discharging position and the gear 79 drives the gear segment 73 to swing the arm 74 with the knife 66 out from the closed position of the latter and into open position with respect to the discharging position of pocket 63.

Upon the upward stroke of rack 54 the spider 75 is turned with the shaft 31, whereby the arm 80 is disengaged from the roller 81, permitting the guide ring 32 and pocket 63 to be turned with the spider 75 by means of the spring 68 and thus returning the pocket 63 to its closed position under the knife 67, and permitting the spring 68' to return the arm 74 with the knife 66 to the closed position of the latter with respect to the pocket 63. As the spider 75 continues turning with the shaft 31 during the upward stroke of the rack 54 the lug 107 of arm

74 meets stop screw 109, whereupon the arm 74 is stopped while the pocket 63 continues moving relatively to the now stationary knife 66 until it reaches filling position. During this movement of the pocket 63 to filling position, while the movement of the arm 74 is obstructed by stop screw 109, the epicyclic gear 79 is turned by the now stationary gear segment 73 to cause the epicyclic gear 78 to turn the gear segment 72 backwardly with the pocket 63 relative to the knife 67 so that the latter will be in open position when the pocket 63 finally arrives at filling position.

It will be observed that the hopper outlet is closed by the knife 67 while the pocket 63 is in transit to and from discharging position. For this purpose the length of the knife 67 must be sufficient to close the hopper outlet when the knife is at the limit of its forward swing. When the knives 66, 67 are opened at the discharging and filling positions of the pocket 63, by the roller 81 or by the stop screw 109, respectively, and when they are being closed again on leaving these positions, the relative motion of the parts 63, 66 and 67 is such that the gap between knives is always central of the pocket.

It may be noted that the knife 67, Fig. 3, is positively actuated since it is rigidly connected to the shaft 31, by the spider 75. The reason for positively operating the knife or jaw 67 is 30 that this is the knife which cuts off any straggling scraps, by carrying these scraps past a stationary shear blade 66a arranged beside the path of movement of the jaws as shown in Fig. 2B, and when this knife was spring closed, as 35 in prior constructions, these scraps would hold the jaw open against the tension of the spring. A scraper 67a prevents scrap from being caught between the wrapper and transfer on its return.

The operation of the knives or parting jaws 40 66 and 67 is different from those of the machine disclosed in said Patent No. 1,915,525 in that the jaws do not suddenly snap closed before movement of the transfer drum but the jaws close as the transfer pocket starts moving them. An 45 important difference in the present construction is that the pocket is right up against the bottom of the hopper so that its curvature causes it to enter the hopper outlet so that it is not necessary to give the pocket a separate movement up into 50 the hopper. This also avoids trouble due to the tobacco leaking through the space between the knives and the vertical walls of the hopper outlet. Also this makes for a much simpler and cheaper pocket construction and eliminates expensive fitting and machining.

The bottom of pocket 63 is provided with a perforated false bottom 111 and has a duct 112 communicating with a pipe 113 fitting into a bore of a disk 114 turning on the hub of arm 74. The 60 bore in the disk 114 registers with a duct in pedestal 17 when the pocket 63 is in filling position, so that in this position the contents of the pocket are subjected to the action of suction by means of a pipe 115 communicating through the duct 65 in the pedestal 17 with the pipe 113 and connected to a suction chamber 116 attached to base 16, the suction chamber being provided with a pipe 117 leading to a suitable suction unit (not shown). Each quantity of tobacco in the pocket 63 is thus 65 freed of dust as it enters the same.

The rings 32 are guided by plates 118 attached to lugs 119 of the hopper 30, the lugs 119 also carrying housings 81 and 81'. On a bent rod 120 fastened in a lug of the rear housing 81 there is 75

adjustably mounted a chute 121 which directs the quantity of tobacco T' discharged from pocket 63 into a conduit leading to the measuring chamber 33. The tobacco is thrown at an angle to the surface of the chute so that the chute has a placing effect (for instance by tilting the chute, the proper amount of tobacco for tapered bunches can be placed toward one end of the bunch), and also the impact of the tobacco on the chute tends to break up wads of tobacco. With the old constructions, the tobacco was thrown in the direction of the length of the chute so that some tobacco did not even touch the walls of the chute and therefore the chute had very little placing effect.

The front housing 81', in lugs provided for this purpose, carries a transverse shaft 122 which is tensioned by a spring 131 and to which a curved tray 132 is affixed, in position to receive any tobacco spillage from the pocket 63, Figs. 1 and 2. The tray 132 is connected by a link 136 to a lever 137 loose on shaft 21. Link 136 is slotted at its joint with tray 132 to allow lever 137 sufficient movement for opening the gate 82 of the measuring chamber 33 before swinging out the tray 132 to discharge the accumulated tobacco spillage into the measuring chamber 33.

The lever 137 is actuated by a pin 89 carried by an arm 22' of lever 22, loosely mounted on shaft 21, this pin engaging with an adjusting screw 90 in lever 137 when actuated by the cam rod 83 from the cam lever 84 controlled by cam 25. The free end of lever 137 is connected by a link 138 with a lever 145 attached to the hinge shaft 91 of gate 82 which is normally held in position to form the top of the measuring chamber 33 with the stop screw 146 of lever 145 in abutting relation with a pin 147 in one of a pair of spaced bars 150, by the action of a spring 151 fastened to lever 137 and pedestal 17. The bars 150 are supported on a cross-piece 86 fastened to bar 34 and the ledger plate 92 attached to the frame 19. Slidable in holes in bars 150 are the pins 150a of a pair of parallel plates 150b which form the sides of the measuring chamber 33 which thus is made adjustable within given limits, the pins 150a being held in their desired positions by set screws in bars 150. By this means the length of the bunch may be regulated by adjustment of the plates 150b. This feature is believed to be new and important as it makes it possible to dispense with several dozen model parts and makes the change over from a bunch of one length to another a very simple matter.

When the gate 82 is open, as shown in dotted lines in Fig. 1, it forms the rear wall of the conduit referred to above, the same having a front wall 152 and side walls 153. The cam 25 is so timed that the gate 82 is opened while pocket 63 is in filling position and remains open at all times whenever there is any movement of the transfer pocket 63, thus allowing all tobacco dribbling from the pocket during such motion to drop into the measuring chamber 33. Only one gate 82 is used instead of two gates as formerly because the edges of the gates came together where the pile of tobacco delivered was highest and pinched tobacco. With one gate as here, the tobacco is directed somewhat away from closing edge of the gate and the gate closes at the point where pile is low.

The column of loose tobacco T' deposited in the measuring chamber 33 is forced into the chamber 36 and compressed therein by the plunger 35, Fig. 1, which is fastened to a rod 93 sliding in a

lug 94 of slide 95 supported on bar 34. A spring 96 on rod 93 bears against the end of plunger 35 and is adjusted to the proper tension by a block 97 clamped on a rod 98 slidably in the lug 94, the tension of the spring 96 determining the density of the tobacco compressed by the plunger 35. The slide 95 is connected by a link 99 to a cam lever 100 having a cam roller 101 in engagement with the cam groove of face cam 27. In order to gather the column of tobacco T' into a more or less parallelipedal shape before compressing the same, the cam track of cam 27 is so shaped (Fig. 1) that the plunger 35 during its forward movement has a hammering motion, going forward and back a number of times before its final forward stroke, thus obtaining a uniform density in the column of tobacco and eliminating voids. The rod 93 carries a finger 102 which normally engages a trip lever 103 pivoted on support block 18 and connected through a rod 108 to the ratchet drive of the rack 54 to control the same in the manner described in the patent referred to above. When the accumulation of surplus tobacco in the measuring chamber has reached a certain limit, which may correspond to an excess sufficient for one or more additional bunch charges, the plunger 35 does not travel far enough to permit the finger 102 to engage lever 103, whereby the ratchet drive of rack 54 is incapacitated, thus preventing the oscillation of the feed pocket 63 during the next cycle of the machine.

When the charge-measuring pocket 36 has been filled and the tobacco fully compressed by the advance of plunger 35, the vertical rod 123 in frame 19 descends, thereby operating the charge-cutting knife 124 and the charge transfer 37, the rod 123 being actuated by a cam lever 125 having a roller 126 in a track of face cam 27.

To the slide rod 123, Figs. 5 to 7, is clamped a bracket 127 projecting into an opening of a block 128 carried by vertical slides 129 in frame 19 and affixed to said block by a pin 130. The slides 129, which are held in their ways in frame 19 by retaining strips 133, carry the knife 124 and in turn form the slideways for rails 134 joined by a tie plate 135. Plates 139 attached to the tops of slide rails 134 and projecting over their slideways, bear on the compression springs 140 seated on blocks 141 attached to slides 129. In the uppermost position of rod 123 the springs 140 hold the plates 139 against horizontal studs 142 in frame 19. On the downstroke of rod 123 the stop screws 144 in plates 143 on the upper ends of the slides 129 engage plates 139 and depress the slide rails 134.

On pins 154 in the lower ends of slide rails 134 are pivoted blocks 158 joined by a plate 159 forming the bottom of the charge measuring pocket 36, the walls forming the sides and the end and the top of pocket 36 being secured to the plate 159. Cam pieces 160 attached to blocks 158 engage pins 161 carried by blocks 165 extending from the bottom ends of strips 133 and thereby turn the pocket 36 downward through one quarter-turn into a vertical position as the same is lowered by the slides 134. Within the pocket 36 there is a plunger 166, the inward movement of which is limited by adjusting screws 167, and the plunger is fixed on guide rods 168 projecting through the wall 159 of pocket 36. After the engagement of the cams 160 with the pins 161 has turned the pocket 36 into the dotted position shown in Fig. 6, the rods 168 are depressed by a horizontal ejecting rod 169 descending with block 128 and the bunch-charge B is thereby

expelled onto the rolling apron or Chianti belt 155 attached at one end to the bunch rolling table 38 by strip 157, and secured at its other end to a cam-actuated apron-tightener arm as shown in the above mentioned patent. The bunch rolling pin 39 held in blocks 162 carried by yoke 163 on the head 164 of the swinging arm 40, then rolls the charge B into a binder previously placed on apron 155 and delivers the bunch B' so formed into a clip 156 at the end of the rolling table.

10 into a cap 100 at the end of the rolling table.

The ejecting rod 169 is held in an arm 170 fulcrumed on a lever 171 pivoted in a lug 172 attached to block 128, and the lever 171 is tensioned by a spring 173 anchored to a bar 114 on block 128. The arm 170 is guided by a bell crank-lever 175 pivoted in bracket 127 and carrying a roller 148 adapted to enter the recess of a cam piece 149 supported by frame 19. As the block 128 descends, the roller 148 snaps into the recess of cam piece 149, thereby turning the levers 171 and 175 into the dotted positions shown in Fig. 6, and causing the ejecting rod 169 to depress the rods 168 with the plunger 166. By means of the mechanism just described, the plunger 166 compresses the rectangular charge T' in pocket 36 into a substantially square charge B on the bunch rolling table before discharging it, thereby putting it into shape necessary for the formation of a perfectly round bunch 30 B. The spring 173 which controls the ejecting pressure on the charge T' in the cutting chambers is adjustable by raising or lowering the bar 114 which for this purpose is provided with elongated slots for its fastening screws.

35 The charge-measuring pocket which serves to transfer the bunch charge to the Chianti belt has no gate to close its open end. There is little tendency for the tobacco to fall out of this chamber ahead of time during transfer because the
40 chamber is lowered while in horizontal position to a point where its open end practically touches the Chianti belt which from then on closes its open end. The relatively narrow charge is delivered at right angles to the Chianti belt and tends to spread out and be broken up to form a bunch without flat sides and the relatively narrow cut surface also minimizes flats on bunches. The same arrangement makes it possible to secure a convenient variation in bunch thickness by adjusting the screws 167 which limit the inward movement of the plunger 166, an important
45 50 feature of the present device.

The term "knife" as applied to the arcuate members 66 and 67 should be understood as being employed in a generic sense to refer to a blade (which may be blunt) or to parting or separating devices to part one portion of a mass of loose material from another. Therefore unless otherwise specified, this term as used in the specification and claims is not to be construed as limited to a device having an edged, cutting or shearing action.

What is claimed is:

65 1. The combination with a hopper for holding
a supply of scrap tobacco, said hopper being pro-
vided with an outlet in its bottom, of a transfer
pocket underlying said outlet, a measuring cham-
ber underlying said pocket and provided with a
70 hinged gate adapted to be swung open to admit
tobacco to the measuring chamber, mechanism
for intermittently oscillating said pocket to move
it into registry with the outlet of said hopper to
receive a quantity of tobacco therefrom and then
75 carry said quantity into position above said meas-

uring chamber for delivery thereto, means independent of said mechanism for swinging open said gate while said pocket is in filling position and keeping it open while said pocket oscillates, knives coacting to separate the quantity of tobacco in said pocket from the mass of tobacco in said hopper and then confine it in said pocket while it is being carried into position above said measuring chamber, means for closing and separating said knives, means for compressing the tobacco deposited in said chamber, and means for severing a bunch charge from the compressed column of tobacco in said chamber and transferring the severed charge to bunch rolling position. 15 10

2. The combination with a hopper for holding a supply of scrap tobacco, said hopper being provided with an outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, means independent of said mechanism for swinging open said gate while said pocket is in filling position and keeping it open while said pocket oscillates, knives coacting to separate the quantity of tobacco in said pocket from the mass of tobacco in said hopper and then confine it in said pocket while it is being carried into position above said measuring chamber, means for closing and separating said knives, means for compressing the tobacco deposited in said chamber, and means for severing a bunch charge from the compressed column of tobacco in said chamber and transferring the severed charge to bunch rolling position, said mechanism including a shaft on which said pocket is loosely mounted, a reciprocating rack geared to said shaft, and a spider fast to said shaft and having an arm adapted to move said pocket from filling to discharging position.

3. The combination with a hopper for holding a supply of scrap tobacco, said hopper being provided with an outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, means independent of said mechanism for swinging open said gate while said pocket is in filling position and keeping it open while said pocket oscillates, knives coacting to separate the quantity of tobacco in said pocket from the mass of tobacco in said hopper and then confine it in said pocket while it is being carried into position above said measuring chamber, means for closing and separating said knives, means for compressing the tobacco deposited in said chamber, and means for severing a bunch charge from the compressed column of tobacco in said chamber and transferring the severed charge to bunch rolling position, said compressing means including a compressing plunger and mechanism for imparting a hammering motion to said plunger while it is compressing the column of tobacco in

said measuring chamber, whereby the tobacco will be distributed evenly in the column.

4. The combination with a hopper for holding a supply of scrap tobacco, said hopper being provided with an outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, means independent of said mechanism for swinging open said gate while said pocket is in filling position and keeping it open while said pocket oscillates, knives coacting to separate the quantity of tobacco in said pocket from the mass of tobacco in said hopper and then confine it in said pocket while it is being carried into position above said measuring chamber, means for closing and separating said knives, means for compressing the tobacco deposited in said chamber, and means for severing a bunch charge from the compressed column of tobacco in said chamber and transferring the severed charge to bunch rolling position, said charge-severing and transferring means including a vertically reciprocable slide-rod, a charge-cutting knife supported from said rod, a charge-measuring pocket normally supported from said rod in a horizontal position aligned with the measuring chamber to form a continuation thereof, a device for turning said pocket into a vertical position after the charge therein has been severed by said knife, and mechanism for ejecting the charge from said pocket when the latter is in a vertical position.
5. The combination with a hopper for holding a supply of scrap tobacco, said hopper being provided with an outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, means independent of said mechanism for swinging open said gate to open it while said pocket is in filling position and keeping it open while said pocket oscillates, knives coacting to separate the quantity of tobacco in said pocket from the mass of tobacco in said hopper and confine it in said pocket while it is being carried into position above said measuring chamber positive means for closing and separating said knives, means for compressing the tobacco deposited in said chamber, and means for severing a bunch charge from the compressed column of tobacco in said chamber and transferring the severed charge to bunch rolling position.
6. The combination with a hopper for holding a supply of scrap tobacco, said hopper having outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring

chamber for delivery thereto, means independent of said mechanism for swinging open said gate and keeping it open while said pocket oscillates, knives coacting to separate the quantity of tobacco in said pocket from the mass of tobacco in said hopper and confine it in said pocket while it is being carried into position above said measuring chamber, means for closing and separating said knives, means for compressing the tobacco deposited in said chamber, means for severing a bunch charge from the compressed column of tobacco in said chamber and transferring the severed bunch charge to bunch rolling position, and means controlled by said tobacco compressing means for incapacitating said mechanism when there is a quantity of tobacco sufficient for more than two bunch charges in the measuring chamber and thereafter rehabilitating said mechanism.

7. The combination with a hopper for holding a supply of scrap tobacco, said hopper being provided with an outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, means independent of said mechanism for swinging open said gate while said pocket is in filling position and keeping it open while said pocket oscillates, knives coacting to separate the quantity of tobacco in said pocket from the mass of tobacco in said hopper and confine it in said pocket while it is being carried into position above said measuring chamber, means for closing and separating said knives, means for compressing the tobacco deposited in said chamber, a bunch rolling table, and means for severing a bunch charge from the compressed column of tobacco in said chamber and transferring the severed charge to said bunch rolling table.

8. The combination with a hopper for holding a supply of scrap tobacco, said hopper being provided with an outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, means independent of said mechanism for swinging open said gate while said pocket is in filling position and keeping it open while said pocket oscillates, knives coacting to separate the quantity of tobacco in said pocket from the mass of tobacco in said hopper and confine it in said pocket while it is being carried into position above said measuring chamber, means for closing and separating said knives, means for compressing the tobacco deposited in said chamber, a bunch rolling table, and means for severing a bunch charge from the compressed column of tobacco in said chamber and transferring the severed charge to said bunch rolling table, said charge-severing and transferring means including a vertically reciprocable slide-rod, a charge-cutting knife supported from said

rod, a charge-measuring pocket normally supported from said rod in a horizontal position aligned with the measuring chamber to form a continuation thereof, a device for turning said pocket into a vertical position after the charge therein has been severed by said knife, and mechanism for compressing the charge into substantially square cross-section on the table and ejecting the compressed charge from said pocket 10 while the latter is in a vertical position.

9. The combination with a hopper for holding a supply of scrap tobacco, said hopper being provided with an outlet in its bottom, of a transfer pocket underlying said outlet, a measuring chamber underlying said pocket and provided with a single hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, a housing extending from the outlet of said hopper to a position above said gate, knives coacting to separate the quantity of tobacco in said pocket from the mass of tobacco in said hopper and confine it in said pocket while it is being carried into position above said measuring chamber, means for closing and separating said knives, a tray underlying the lower end of said housing to receive tobacco spillage from said pocket, means independent of said mechanism for swinging open said gate and then swinging out said tray, whereby the tobacco spillage accumulated on said tray and the tobacco discharged from said pocket will be delivered to said measuring chamber, means for compressing the tobacco deposited in said measuring chamber, and means for severing a bunch 40 charge from the compressed column of tobacco in said measuring chamber and transferring it to bunch rolling position.

10. The combination with a hopper for holding a supply of scrap tobacco, said hopper being provided with an outlet in its bottom, of a transfer pocket underlying said outlet, a measuring chamber underlying said pocket and provided with a hinged gate adapted to be swung open to admit tobacco to the measuring chamber, mechanism for intermittently oscillating said pocket to move it into registry with the outlet of said hopper to receive a quantity of tobacco therefrom and then carry said quantity into position above said measuring chamber for delivery thereto, a housing extending from the outlet of said hopper to a position above said gate, a chute underlying the lower end of said housing and the discharging position of said pocket to intercept the discharged tobacco so that its impact thereon will break up 50 wads of tobacco, knives coacting to separate the quantity of tobacco in said pocket from the mass of tobacco in said hopper and confine it in said pocket while it is being carried into position above said measuring chamber, means for closing and separating said knives, a tray underlying the lower end of said housing to receive tobacco spillage from said pocket, means independent of said mechanism for swinging open said gate and then swinging out said tray, whereby the tobacco spillage accumulated on said tray and the tobacco discharged from said pocket will be guided into 60 said measuring chamber by said chute, means for compressing the tobacco deposited in said chamber, and means for severing a bunch charge 70 from the compressed column of tobacco in said

chamber and transferring it to bunch rolling position.

11. The combination with a hopper for holding a supply of scrap tobacco, said hopper being provided with an outlet, of a transfer pocket underlying said outlet, a measuring chamber underlying said pocket, mechanism for intermittently oscillating said pocket to move it into registry with the outlet of said hopper to receive a quantity of tobacco therefrom and then carry said 10 quantity into position above said measuring chamber for delivery thereto, knives coacting to separate the quantity of tobacco in said pocket from the mass of tobacco in said hopper and then confine it in said pocket while it is being carried 15 into position above said measuring chamber, means for closing and separating said knives, means for compressing the tobacco deposited in said chamber, and means for severing a bunch charge from the compressed column of tobacco 20 in said chamber and transferring the severed charge to bunch rolling position, one of said knives being adapted to close the hopper outlet when said pocket moves out of filling position.

12. The combination with a hopper for holding 25 a supply of scrap tobacco, said hopper being provided with an outlet, of a transfer pocket underlying said outlet, a measuring chamber underlying said pocket, mechanism for intermittently oscillating said pocket to move it into registry 30 with the outlet of said hopper to receive a quantity of tobacco therefrom and then carry said quantity into position above said measuring chamber for delivery thereto, knives coacting to separate the quantity of tobacco in said pocket 35 from the mass of tobacco in said hopper and then confine it in said pocket while it is being carried into position above said measuring chamber, means for closing and separating said knives, means for compressing the tobacco deposited in 40 said chamber, and means for severing a bunch charge from the compressed column of tobacco in said chamber, one of said knives being adapted to close the hopper outlet when said pocket moves out of filling position. 45

13. The combination with a hopper for holding a supply of scrap tobacco, said hopper being provided with an outlet, of a transfer pocket underlying said outlet, mechanism for intermittently oscillating said pocket to move it into registry 50 with the outlet of said hopper to receive a quantity of tobacco therefrom and then carry said quantity into delivery position, knives coacting to separate the quantity of tobacco in said pocket from the mass of tobacco in said hopper, and 55 means for closing and separating said knives, one of said knives being adapted to close the hopper outlet when said pocket moves out of filling position.

14. The combination with a hopper for holding 60 a supply of scrap tobacco, said hopper being provided with an outlet, of a transfer pocket underlying said outlet, mechanism for intermittently oscillating said pocket to move it into registry with the outlet of said hopper to receive a 65 quantity of tobacco therefrom and then carry said quantity into delivery position, arcuate knives coacting to separate the quantity of tobacco in said pocket from the mass of tobacco in said hopper and confine it in said pocket while 70 the latter moves from filling to delivery position, and means for closing and separating said knives, said mechanism including a shaft on which said pocket is loosely mounted, a reciprocating rack geared to said shaft, and a spider fixed to said 75

shaft and having an arm adapted to move said pocket from filling toward delivery position.

15. The combination with a hopper for holding a supply of scrap tobacco, said hopper being provided with an outlet, of a transfer pocket underlying said outlet, mechanism for intermittently oscillating said pocket to move it into registry with the outlet of said hopper to receive a quantity of tobacco therefrom and then carry said quantity into delivery position, arcuate knives coacting to separate the quantity of tobacco in said pocket from the mass of tobacco in said hopper and confine it in said pocket while the latter moves from filling to delivery position, and means for closing and separating said knives, said mechanism including a shaft on which said pocket is loosely mounted, a reciprocating rack geared to said shaft, and a spider fixed to said shaft and having an arm adapted to move said pocket from filling toward delivery position, and one of said knives being fixed to said spider.

16. The combination with a hopper for holding a supply of scrap tobacco, said hopper being provided with an outlet, of a transfer pocket underlying said outlet, mechanism for intermittently oscillating said pocket to move it into registry with the outlet of said hopper to receive a quantity of tobacco therefrom and then carry said quantity into delivery position, arcuate knives coacting to separate the quantity of tobacco in said pocket from the mass of tobacco in said hopper and confine it in said pocket while the latter moves from filling to delivery position, and means for closing and separating said knives, said mechanism including a shaft on which said pocket is loosely mounted, a reciprocating rack geared to said shaft, and a spider fixed to said shaft and having an arm adapted to move said pocket from filling toward delivery position, and one of said knives being fixed to said spider and of a length sufficient to close the hopper outlet when said pocket is in delivery position.

17. The combination with a hopper for holding a supply of scrap tobacco, said hopper being provided with an outlet, of a transfer pocket underlying said outlet, mechanism for intermittently oscillating said pocket to move it into registry with the outlet of said hopper to receive a quantity of tobacco therefrom and then carry said quantity to discharging position, a pair of arcuate knives coacting to separate the quantity of tobacco in said pocket from the mass of tobacco in the hopper and then confine it in said pocket while the latter moves from filling to discharging position, said mechanism including a shaft on which said pocket is loosely mounted, a reciprocating rack geared to said shaft, and a spider fixed to said shaft and having an arm adapted to move the pocket from filling toward discharging position, and said means including epicyclic gearing connected to said knives for separating the same.

18. The combination with a hopper for holding a supply of scrap tobacco, said hopper being provided with an outlet, of a transfer pocket underlying said outlet, and mechanism for oscillating said pocket to move it into registry with the outlet of said hopper to receive a quantity of tobacco therefrom and then carry said quantity into discharging position, said mechanism including a shaft on which said pocket is loosely mounted, a reciprocating rack geared to said shaft, and a spider fixed to said shaft and having an arm adapted to move said pocket from filling toward discharging position.

19. The combination with a hopper for holding a supply of scrap tobacco, said hopper being provided with an outlet, of a transfer pocket underlying said outlet, mechanism for oscillating said pocket to move it into registry with the outlet of said hopper to receive a quantity of tobacco therefrom and then carry said quantity into discharging position, a housing for covering said pocket while it is moving from filling to discharging position, a tray underlying the lower end of said housing to catch tobacco spillage from said pocket, and means for swinging said tray out of operative position to discharge the tobacco spillage accumulated thereon. 5

20. The combination with a hopper for holding a supply of scrap tobacco, said hopper having an outlet in its bottom, of a transfer pocket, underlying said outlet, mechanism for intermittently oscillating said pocket to move it into registry with the outlet of said hopper to receive a quantity of tobacco therefrom and then carry said quantity into delivery position, and opposed sets of oscillatory agitators for raking the mass of tobacco from the sides of the hopper toward the outlet thereof.

21. The combination with a hopper for holding a supply of scrap tobacco, said hopper having an outlet in its bottom, of a transfer pocket underlying said outlet, mechanism for intermittently oscillating said pocket to move it into registry with the outlet of said hopper to receive a quantity of tobacco therefrom and then carry said quantity into delivery position, opposed sets of oscillatory agitators for raking the mass of tobacco from the sides of the hopper toward the outlet thereof while said pocket is in registry therewith, and means for imparting to said agitators a swinging motion during their forward movement and a substantially axial motion during their backward movement. 40

22. The combination with a transfer pocket, of mechanism for intermittently oscillating said pocket from a position in which it may be filled with tobacco to another position in which the tobacco is discharged, a pair of knives coacting 45 to confine the tobacco in said pocket, and positive means for closing and separating said knives, whereby all scraps projecting therebetween will be severed.

23. The combination with a transfer pocket, of mechanism for intermittently oscillating said pocket from a position in which it may be filled with tobacco to another position in which the tobacco is discharged, said mechanism including a shaft on which said pocket is loosely mounted, 55 a reciprocating rack geared to said shaft, and a spider fixed to said shaft and having an arm adapted to move said pocket from filling to discharging position.

24. The combination with a measuring chamber 60 adapted to receive a quantity of tobacco, of mechanism for compressing the tobacco in said chamber, and means for severing a bunch charge from the compressed column of tobacco in said chamber and transferring the charge to bunch 65 rolling position, said mechanism including a compressing plunger and means for imparting a hammering motion to said plunger while it is compressing said column of tobacco, whereby the tobacco will be distributed evenly in the column. 70

25. The combination with a measuring chamber adapted to receive a quantity of tobacco, of mechanism for compressing the tobacco in said chamber, and means for severing a bunch charge from the compressed column of tobacco in said 75

chamber and transferring the charge to bunch rolling position, said means including a vertically reciprocable slide-rod, a charge-cutting knife supported from said rod, a charge-measuring pocket normally supported from said rod in a horizontal position aligned with the measuring chamber to form a continuation thereof, a device for turning said pocket into a vertical position after the charge therein has been severed by said knife, and mechanism for ejecting the charge from said pocket when the latter is in a vertical position.

26. The combination with a measuring chamber adapted to receive a quantity of tobacco, of mechanism for compressing the tobacco in said chamber, and means for severing a bunch charge from the compressed column of tobacco in said chamber, said mechanism including a compressing plunger and means for imparting a hammering motion to said plunger while it is compressing said column of tobacco, whereby the tobacco will be distributed evenly in the column.

27. The combination with a transfer pocket, of mechanism for intermittently oscillating said pocket from a position in which it may be filled with tobacco to another position in which the tobacco is discharged, a pair of knives coacting to confine the tobacco in said pocket, means for closing and separating said knives, and suction means for removing dust from said pocket while it is in filling position only.

28. The combination with a transfer pocket, of mechanism for intermittently oscillating said pocket from a position in which it may be filled with tobacco to another position in which the tobacco is discharged, a pair of knives coacting to confine the tobacco in said pocket, means for closing and separating said knives, and suction means for removing dust from said pocket while it is in filling position only, said pocket having a perforated false bottom and a dust communicating with the interior of the pocket below said false bottom and said suction means including a stationary pipe arranged to communicate with said duct only while said pocket is in filling position and adapted to be connected to a source of suction.

29. The combination with a transfer pocket, of mechanism for intermittently oscillating said pocket from a position in which it may be filled with tobacco to another position in which the tobacco is discharged, and suction means for removing dust from said pocket while it is in filling position only.

30. The combination with a transfer pocket, of mechanism for intermittently oscillating said pocket from a position in which it may be filled with tobacco to another position in which the tobacco is discharged, and suction means for removing dust from said pocket while it is in filling position only, said pocket having a perforated false bottom and a duct communicating with the interior of the pocket below said false bottom, and said suction means including a stationary pipe arranged to communicate with said duct only while said pocket is in filling position and adapted to be connected to a source of suction.

31. The combination with a vertically reciprocable slide-rod, a charge-cutting knife supported from said rod, a charge-measuring pocket normally supported from said rod in a horizontal position, a device for turning said pocket into a vertical position after a bunch charge therein has been severed by said knife, and mechanism

for ejecting the charge from said pocket when the latter is in a vertical position.

32. The combination with a vertically reciprocable slide-rod, a charge-cutting knife supported from said rod, a charge-measuring pocket normally supported from said rod in a horizontal position, a device for turning said pocket into a vertical position after a bunch charge therein has been severed by said knife, and mechanism for ejecting the charge from said pocket when the latter is in a vertical position, said mechanism including an ejecting plunger slidably mounted in said pocket and adjusting screws for limiting the inward movement of the plunger in said pocket, whereby the thickness of the bunch charge may be varied by adjustment of said screws.

33. In a cigar bunch machine, an enclosure for forming a column of tobacco, having a tobacco receiving opening and a tobacco delivery opening, a chute adjacent said receiving opening, means for delivering scrap tobacco to said chute for gravity movement into said opening, a tobacco charge measuring chamber of rectangular cross-section having one side open, said chamber being substantially greater in depth from the open side to the opposite rear side than in thickness taken at right angles to said depth, arranged to be positioned with its open end registering with one end of said column, means for forcing tobacco of said column into said chamber, a cutter for severing the charge, movable along said opening in the direction of said thickness, a rolling apron, and mechanism for moving said measuring chamber from said registering position to a substantially vertical position with its open side adjacent said apron to deliver the charge edgewise against said apron.

34. The combination with bunch rolling means, of means for providing a mass of tobacco containing more tobacco than is required for the bunch, said mass being of a thickness substantially less than the width of the bunch, means for supporting said mass in horizontal position, a measuring chamber positioned to register with one edge of said mass having the side thereof nearest the mass open, said measuring chamber having a depth from front to back substantially greater than the width of the bunch, and means for moving said chamber from a position with its open side in register with said mass to a vertical position in which it delivers the charge into said rolling means edgewise, a hopper for scrap tobacco on a level above said mass, and means for periodically removing increments of scrap from said hopper and dumping them onto said means.

35. In a scrap bunch cigar machine, the combination with a hopper having a bottom delivery opening and having walls downwardly inclined toward said opening, of elongated agitators located on either side of said opening, and means for giving the tips of said agitators opposite feeding movements along paths relatively close to said walls, and toward said opening and return movements along paths relatively distant from said walls.

36. In a scrap bunch cigar machine, the combination with a hopper having a bottom delivery opening and having walls downwardly inclined toward said opening, of elongated agitators located on either side of said opening, and means for giving the tips of said agitators opposite feeding movements along paths relatively close to said walls, and toward said opening and re-

turn movements along paths relatively distant from said walls, said means including mechanism guiding the agitators for travel in a generally endwise direction during their return movement 5 to render them ineffective during the latter movement.

37. The combination with a hopper for scrap tobacco having an outlet in its bottom portion, a transfer member having a cylindrical surface fitting 10 said outlet with the curvature of said surface extending upwardly into said hopper, a transfer pocket in said member adjoining said surface, mechanism for imparting intermittently oscillating movement to said member to move said pocket upwardly through said outlet and into said hopper as a result of said movement, knives adjacent 15 opposite sides of said pocket, and means for operating at least one of said knives relative to the pocket while the pocket is within the hopper to separate the tobacco within the pocket from the remaining tobacco in the hopper.

38. The combination with a hopper for scrap tobacco having an outlet in its bottom portion, a transfer member having a cylindrical surface fitting 20 said outlet with the curvature of said surface extending upwardly into said hopper, a transfer pocket in said member adjoining said surface, mechanism for imparting intermittently oscillating movement to said member to move said pocket upwardly through said outlet and into said hopper as a result of said movement, knives adjacent 25 opposite sides of said pocket, and means for operating at least one of said knives relative to the pocket while the pocket is within the hopper to separate the tobacco within the pocket from the remaining tobacco in the hopper, said means including mechanism mounting said knife on the transfer member for movement thereon relative to the member.

40. 39. The combination with a hopper for scrap tobacco having an outlet in its bottom portion, a transfer member having a cylindrical surface fitting 30 said outlet with the curvature of said surface extending upwardly into said hopper, a transfer pocket in said member adjoining said surface, mechanism for imparting intermittently oscillating movement to said member to move said pocket upwardly through said outlet and into said hopper as a result of said movement, knives adjacent 35 opposite sides of said pocket, and means for operating at least one of said knives relative to the pocket while the pocket is within the hopper to separate the tobacco within the pocket from the remaining tobacco in the hopper, said means including mechanism actuating each of said knives toward the other.

40. The combination with a hopper for scrap tobacco having an outlet in its bottom portion, a transfer member having a cylindrical surface fitting 40 said outlet with the curvature of said surface extending upwardly into said hopper, a transfer pocket in said member adjoining said surface, mechanism for imparting intermittently oscillating movement to said member to move said pocket upwardly through said outlet and into said hopper as a result of said movement, knives adjacent 45 opposite sides of said pocket, and means for operating at least one of said knives relative to the pocket while the pocket is within the hopper to separate the tobacco within the pocket from the remaining tobacco in the hopper, said knife being arcuate in shape to conform to the curvature of said transfer member.

41. The combination with a hopper for scrap 75 tobacco having an outlet, a transfer member, a

tobacco receiving pocket in said member, mechanism for imparting to and fro movement to said member to move the pocket to and from tobacco receiving relationship to said outlet, a knife movably mounted on said member adjacent one side of said pocket, and means for positively operating said knife in the direction of return movement of the pocket while the pocket is at said outlet to separate the tobacco within the pocket from the remaining tobacco, whereby return movement of the member will not tend to open the knife through resistance of scraps remaining at the outlet.

42. A portioning device for scrap bunch machines comprising a hopper for scrap having an outlet in its lower portion a pair of opposed jaws mounted for movement toward and away from each other and for movement in unison about a generally horizontal axis below said outlet, actuating means for swinging said jaws about said axis into said hopper and relative to each other separate a portion from the tobacco in the hopper, and for then swinging the jaws in unison to withdraw the separated portion, and extended arcuate parts adjacent the operating parts of said jaws fitting the outlet opening in said hopper and operating to prevent passage of tobacco from the hopper other than between the opposed portions of said jaws.

43. A portioning device for scrap bunch cigar 30 machines comprising a hopper for scrap having an outlet, a scrap transfer member having a to and fro motion from tobacco receiving position at said outlet to a tobacco delivering position distant from said outlet, jaws on said member at 35 least one of which is movable toward another at tobacco receiving position to retain a tobacco portion, said jaws being subject to having straggling scraps projecting from between the jaws, and a relatively stationary knife coacting with 40 the jaws to shear off said projecting scrap.

44. In a cigar bunch machine, an enclosure for forming a column of tobacco, having a tobacco delivery opening, a tobacco charge measuring chamber having one side open, said chamber 45 being substantially greater in depth from the open side to the opposite rear side than in thickness taken at right angles to said depth to produce a charge of greater depth than thickness, arranged to be positioned with its open end regis- 50 tering with one end of said column, means for forcing the tobacco of said column into said chamber, a cutter for severing the charge in said chamber, movable across said opening in the direction of said thickness, a bunch rolling apron, 55 and mechanism for moving said measuring chamber from said registering position to a position with its open side adjacent said apron to deliver the charge edgewise against said apron, a plunger in said chamber facing said open side, and means 60 operating said plunger to eject the charge and compress it edgewise against said apron to render the depth and thickness of the charge substantially equal before rolling.

45. In a cigar bunch machine, a tobacco charge 65 measuring chamber having one side open, said chamber being substantially greater in depth from the open side to the opposite rear side than in thickness taken at right angles to said depth to produce a charge of greater depth than thick- 70 ness, means for pushing tobacco into said chamber, a cutter for severing the charge, movable along said open side, in the direction of said thickness, a rolling apron, and mechanism for moving said measuring chamber from tobacco 75

receiving position to a position with its open side adjacent said apron to deliver the charge edge-wise against said apron, a plunger in said chamber facing said open side, and means operating said plunger to eject the charge and compress it edgewise against said apron, said means including a yieldable device for placing a predetermined compressing pressure on said plunger.

46. In a cigar bunch machine, a tobacco charge measuring chamber having one side open, means for forcing tobacco into said chamber, a cutter for severing the charge, movable along said open

side, a rolling apron, and mechanism for moving said measuring chamber from tobacco receiving position to a position with its open side adjacent said apron to deliver the charge against said apron, a plunger in said chamber facing said open side, and means operating said plunger to eject the charge and compress it against said apron, said means including a spring for placing a predetermined compressing pressure on said plunger, and devices for adjusting the tension of said spring to vary the pressure on said plunger.

JOHN F. HALSTEAD.
